UNITED STATES PATENT OFFICE.

CLAUDE A. P. TURNER, OF MINNEAPOLIS, MINNESOTA.

LONG-SPAN CANTALIVER-BRIDGE.

1,256,081.

Specification of Letters Patent. Patented Feb. 12, 1918.

Application filed December 22, 1909. Serial No. 534,534.

To all whom it may concern:

Be it known that I, CLAUDE A. P. TURNER, of Minneapolis, in the county of Hennepin and in the State of Minnesota, have invented a certain new and useful Improvement in Long-Span Cantaliver-Bridges, and do hereby declare that the following is a full, clear, and exact description thereof.

My invention more particularly relates to long span cantaliver bridges, and my object is to facilitate and reduce the cost of erection of such bridges, and to give them all required strength, and to this end my invention consists in the features of construction substantially as hereinafter specified and claimed.

Referring to the accompanying drawings, Figure 1 is a view in the nature of a diagram of enough of a cantaliver bridge to illustrate an embodiment of my invention;

Fig. 1^a is a similar view illustrating the utilization of the first inclined main post in the work of erecting the river arm.

Fig. 2 is a side elevation of a portion of one of the main compression chord members constructed in accordance with my invention;

Fig. 3 a horizontal section on the line C—C of Fig. 2;

Fig. 4 a cross section on the line B—B of Fig. 2; and

Fig. 5 a cross section on the line A—A of Fig. 2.

In a cantaliver bridge, such as that at Quebec, having a span of eighteen hundred feet, a single intersection Warren type of main members is most economical, because of the extreme height essential for moment over the piers and the economic reduction in depth of the truss as we approach the an-

chorage or proceed toward the center. I therefore use the single intersection Warren type of main member.

The single intersection Warren type is, as shown in the drawings, one wherein the web consists of

one series of triangles formed by the inclined bars extending between the upper and lower chords. In the embodiment of my invention illustrated in the drawings, the vertical post member 10 over the main pier 11 is trussed

in diamond shape, and from it extend the top chord 12 and the bottom chord 13 of the cantaliver arm. In putting up the first inclined main post or cantaliver member 1—2

(which in the case of the bridge shown is approximately two hundred and thirty feet

long), I tie it at mid-length to a strut 3—4, 4—3, this being done as the first half, or the part 1—3 in the first inclined main post is erected. The use of this intermediate stay as a chord in erection contributes to the convenient putting up of the cantaliver arm. When the point 7, or the second inclined main post in the span is reached, by the use of an intermediate tie 5—6, the erection of the structure beyond the point 7 is possible by putting up the member 7—6, then 8—6, 6—9 and 8—9, simultaneously. Beyond this point, the erection involves no special features.

The panels in the case of the bridge illustrated, will be between fifty and sixty feet, and the usual eye-bar top chord is supported at regular intervals by vertical members 14 that in the main carry merely the weight of the chord. This type of construction has the advantage of making vary few main joints in connection with the bar chain, which is used throughout the top chord.

It will be perceived that the sub-bracing that connects the central portion of the web members forms therewith and with the bottom chord a complete cantaliver sub-truss. In the case of the bridge shown the vertical post member 10 is some 300 feet high and, therefore, of many tons in weight, that results in distorting effects and secondary strains resulting therefrom, during erection, that involve the members of the sub-truss and cause alterations of their relative positions that call for adjustment of the parts. By using the diamond shape truss for the vertical post member, I am able to accomplish such adjustment which may be done by the wedge device commonly employed in bridge work, and applied to the lower side members of the diamond truss.

As frequently built in the United States, heretofore, the huge members in compression for the bottom chord have been defective, the failure of the first attempt to construct the eighteen hundred foot bridge at Quebec indeed being due to this, the chords in that case having been made up of channels with heavy verticals and light lacing. In the embodiment of my invention I prefer to employ a main compression chord member having all required strength, and yet convenient or easy of construction. Said member is of sectional make up and it comprises a plurality, preferably, but not neces-

sarily, three longitudinally extending parallel webs 15 that at top and bottom have heavy flanges 16, and which are connected at the top by a cover plate 17. To stiffen 5 the webs at the center, I have a concentration of metal in the form of longitudinally extending ribs 18, and at intervals of three to four times the depth of the chord I connect the webs transversely with diaphragms 10 19, and the central ribs 18 and the bottom flanges 16 are connected together at intervals between the diaphragms by transverse strut-forming bars 20. By the construction described and illustrated, ample access may 15 be had to the interior or inside to drive rivets to connect the web members, and the resulting structure, while much simplified, is one all of whose parts are rigid under compression.

20 In Fig. 1^a the first inclined main post 1—2 is shown as suspending a bridge member in work of erecting the river arm.

What I claim is—

In a cantaliver span, the combination of the main pier, the vertical post member 25 mounted thereon, trussed in diamond shape, top and bottom chords extending outward from said post, webbing connecting said chords, including an inclined main post that extends to the top chord, upward and outward from the bottom chord, and a tie that extends from the vertical post truss at substantially mid-length thereof to substantially mid-length of said inclined main post and constitutes the tension member of sub-truss 30 35 whose compression member is the bottom chord.

In testimony that I claim the foregoing I have hereunto set my hand.

CLAUDE A. P. TURNER.
